UNITED STATES PATENT OFFICE.

GEORGE W. DOVER, OF CRANSTON, RHODE ISLAND.

PIN-JOINT.

SPECIFICATION forming part of Letters Patent No. 729,556, dated June 2, 1903.

Application filed November 12, 1902. Serial No. 130,951. (No model.)

To all whom it may concern:

Be it known that I, GEORGE W. DOVER, a citizen of the United States, residing at Cranston, in the county of Providence and State of Rhode Island, have invented certain new and useful Improvements in Pin-Joints, of which the following is a specification.

My invention relates to pins and brooches intended for personal wear, and particularly to the joint and parts adjacent thereto and connected therewith.

A well-known disadvantage exists in rigidly fixing a pin-tongue to the body of a brooch or similar ornament in that the heat involved in soldering the pin to the brooch devitalizes that portion of the pin-stem where the greatest spring is imperative.

I seek to obviate the weakness above pointed out and gain additional structural advantages, including facility of assemblage, by the construction hereinafter detailed, and shown in the drawings, wherein—

Figure 1 is a side elevation of my new pin-joint; Fig. 2, a similar view of the same, showing the housing in vertical central section; Fig. 3, a detail view of the housing in original form; and Fig. 4, a view of the latter after being pinched to final position, said view being taken on line $\alpha\alpha$ of Fig. 2.

Similar reference-letters refer to like parts in the above views.

My improvement is embodied as follows: To the front or body A of a brooch or similar ornament is soldered at its lower edge a semi-elliptical-shaped housing B, having parallel vertical sides or walls a and flat base d , as in

Fig. 3. This housing is soldered along its flat base d to the body or plate A. It will be seen that this flattened formation furnishes a complete and stable contact and preserves the equilibrium of the housing during the soldering. After the soldering operation the pin-tongue is inserted within the housing B. The pin portion b is substantially straight; but the blunt end c is crooked or folded back into the vertical plane of the pin portion and forms a foot which preferably terminates some distance within the housing; but it may, if preferred, be arranged flush with the same. After insertion of the pin-tongue, as described, the side walls a of the housing B are pressed together by a foot-press or other convenient means into the form shown in Fig. 4, whereby the crook of the pin-tongue is held rigidly against displacement.

It will be noted that by soldering the bottom of the housing to the brooch no portion of the pin member is exposed to the flame.

Having thus described my invention, what I claim is—

In a pin, the combination with the plate of a semi-elliptical housing, with contacting side walls, and a pin-tongue provided with a crooked blunt end, said end being held in position by the compression of said walls.

In testimony whereof I have affixed my signature in presence of two witnesses.

GEORGE W. DOVER.
